(57) **CLAIM**

The ornamental design for an optical lens, as shown and described.

DESCRIPTION

FIG. 1 is a perspective view of an optical lens showing our new design.

FIG. 2 is a front elevational view thereof.

FIG. 3 is a rear elevational view thereof.

FIG. 4 is a left-side elevational view thereof.

FIG. 5 is a right-side elevational view thereof.

FIG. 6 is a top plan view thereof.

FIG. 7 is a bottom plan view thereof.

FIG. 8 is a cross sectional view of the optical lens taken along line A-A of FIG. 6; and,

FIG. 9 is a cross sectional view of the optical lens taken along line B-B of FIG. 6.

The portions of the optical lens shown in broken lines are for illustrative purpose only and form no part of the claimed design.
